UNITED STATES PATENT OFFICE

VICTOR KALFUS, OF NEW YORK, N. Y.

CONVERTIBLE TOOL

Application filed September 6, 1928. Serial No. 304,313.

The invention relates to a new and improved tool construction and has for its primary object to provide such structural features as to enable conversion of the tool for numerous uses, for instance, to reduce pipes and tubes, to cut pipes and the like, to reduce the diameter of shafts, to form circumferential grooves, to reduce lead pipes for snug fitting around a bushing when making joints, and to hold the work while cutting screw threads thereon or performing other operations.

With the foregoing in view, the invention resides in the novel subject matter herein-after described and claimed, description being accomplished by reference to the accompanying drawings.

Fig. 1 is a side elevation partly broken away and in section.

20 Figs. 2, 3 and 4 are sectional views on the correspondingly numbered lines of Fig. 1.

Fig. 5 is a side elevation showing the tool conditioned for use as a vise.

Fig. 6 is a side elevation partly broken away and in section showing a different form of die holder and a different arrangement of rollers.

Fig. 7 is a side elevation partly broken away and in section, showing still further features of construction.

Figs. 8, 9 and 10 are sectional views on the correspondingly numbered lines of Fig. 7.

The features of construction selected for illustration in the present application, may be considered as preferred, with the understanding that within the scope of the invention as claimed, variations may be made.

The numeral 12 on the drawings, denotes a one-piece, continuous yoke having a longitudinal opening 13 through one end, while its opposite end is preferably internally recessed as at 14. One longitudinal side of the yoke 12 is formed with a plurality of spaced openings 15 and its opposite side is provided with a longitudinal slot 16, for purposes to appear, and one of said yoke sides is formed with a socket 17. When the tool is to be operated by hand, a handle 18 is threaded into this socket, but when the

tool is to be converted for use as a vise, a standard 19 is threaded into said socket, said standard being rigidly secured to a base 20, which base is to be fastened upon an appropriate support, by bolts, machine screws 55 or the like 21 (see Fig. 5).

Two flat, arcuate plates 22, varying somewhat in design as occasion may demand, are applicable to opposite sides of the yoke 12, at the end of the latter provided with the recess 14 and the inner portions of these plates project beyond the inner edge of the yoke to form therewith a channel. The plates are secured removably to the yoke by bolts or other desired fasteners 23 and one set of plates may be removed and another substituted according to the character of work to be done. Disposed in the above described channel, are work-engaging rollers 24 which, by screws or other desired means 70 24^a, are mounted upon the inwardly projecting portions of the plates 22. These rollers may be disposed in any desired relation with each other and they may have any necessary configuration according to the character of work to be done, for instance upon a pipe.

25 denotes two flat metal plates applicable against opposite sides of the yoke 12, at the end thereof provided with the opening 13. Each of these plates is provided with parallel longitudinal edges 26 and with a central longitudinal slot 27. Headed screws 28 pass through the slots 27 and are threaded into the yoke 12, other headed screws 29 are threaded into said yoke and engage the edges 80 26, and additional guides 30 are fastened by screws or the like 31 to the yoke to engage the edges 26. Portions of the guides 30 and the heads of the screws 28-29, lie slidably against the outer sides of the plates 25 to hold the latter in proper position, while permitting sliding of said plates toward and from the rollers 24. An adjusting screw 32 is threaded through the opening 13 for effecting sliding of the plates 25 toward the 85 rollers 24, and said plates are preferably provided with portions 33 to be gripped by hand for the purpose of withdrawing said plates upon loosening of said screw.

90 Any desired form of die or the like may 100

be held between the front or inner ends of the plates 25, the shape, construction, size, etc. varying according to the work to be accomplished. In Figs. 1 and 2, for instance, 5 a die is shown comprising a body 34 and work-engaging rollers 35, said body being mounted between the front ends of the plates 25 by means of a screw 36. The rear end of this body is formed with a concave socket 10 37 and the front end of the screw 32 is rounded as at 38 and received in this socket. Thus, all forward thrust of the screw in moving the die against the work, is exerted directly upon this die, the plates 25 merely 15 serving as holding and guiding means for the latter.

Fig. 5 disclosing the tool conditioned for use as a vise, illustrates a die or jaw 39 held between the front ends of the plates 25 by 20 the screw 36, and engaged by the screw 32.

In Fig. 6, a die 40 is shown similar to the die 34-35, but it could be of any other desired construction. Plates 41 lie against opposite sides of this die and are connected 25 with it by a screw 42, and another screw or other appropriate fastener 43 passes through the outer ends of these plates. These plates lie against opposite sides of the yoke 12 and the fastener 43 may either pass through one 30 of the openings 15, or through the slot 16, as may be most advisable. The rear end of die 42 is provided with a shallow socket 44 receiving the rounded front end 38 of the screw 32. When this screw is adjusted, the 35 plates 41 swing about the fastener 43 as a pivot if this fastener be passed through one or another of the openings 15, but the fastener may merely slide, if it passes through the slot 16. The openings 15 or the slot 16, 40 permit setting of the die 40 closer to or farther from the rollers 24, according to the size of the pipe or the like to be reduced or otherwise operated upon.

In Figs. 7 to 10, arms 41^a correspond to 45 the plates 41 but are integral at their inner ends with a head 45 carrying rollers or other desired dies or the like 46. Head 45 is provided with a shallow socket 47 to receive the rounded front end 38 of the screw 32. 50 The arms 41^a are provided with openings to receive a screw or the like 48 which may pass either through the slot 16 or through one or another of the openings 15, as occasion may demand.

55 When the plates 41 or the arms 41^a and associated features of construction are to be used, the plates 25 are of course removed, and vice versa, the use of the plates 41 being most desirable for some uses, the arms 41^a 60 for other uses, and the plates 25 for still other purposes.

Excellent results may be obtained from the general construction shown and described and it is therefore preferably followed, as above stated. However, attention 65

is again invited to the fact that within the scope of the invention as claimed, numerous variations may be made. Moreover, dies or other work-performing or work-engaging members of any appropriate sizes, shapes, 70 relations, etc., may be employed, according to the character of the work to be accomplished.

I claim:—

1. A tool of the class described comprising a continuous yoke having an opening at one end, two arcuate plates lying against opposite sides of said yoke at the other end thereof, means detachably securing said plates to said yoke, both of said plates projecting inwardly from the inner edge of said yoke to form therewith a channel, work-engaging rollers received in and projecting from said channel, means rotatably mounting said rollers on said projecting portions of said plates; a screw threaded through the aforesaid opening, and a die holder movably connected with said yoke and movable toward said rollers under the influence of 80 said screw.

2. A tool of the class described comprising a continuous yoke having parallel longitudinal sides, an opening at one end and work-engaging rollers at its other end, two die-holding plates lying slidably against the opposite faces of both longitudinal sides of 90 said yoke at said one end thereof, means slidably mounting said plates on said longitudinal sides of the yoke, a die mounted between the inner ends of said plates, and a screw threaded through the aforesaid opening for adjusting said plates and die bodily, said screw being received between the portions of said plates behind said die and abutting the latter, said portions of the plates behind the die slidably straddling said one end of said yoke.

3. A tool of the class described comprising a yoke having an opening at one end and work-engaging rollers at its other end, two die-holding plates lying slidably against opposite sides of said yoke at said one end thereof, said plates each having parallel longitudinal edges and a central longitudinal slot, headed screws threaded into said 110 yoke and contacting with said edges and the side walls of the slots, the heads of said screws lying slidably against the outer sides of said plates, and a screw threaded through the aforesaid opening for adjusting said plates and die bodily.

4. A tool of the class described comprising a continuous yoke having parallel longitudinal sides, an opening at one end and work-engaging rollers at its other end, two die-holding plates lying slidably against the opposite faces of both longitudinal sides and said one end of the yoke, means projecting from said faces of said longitudinal sides and said one end for slidably mounting said 120

plates on said yoke, a die mounted between the inner ends of said plates, and an adjusting screw threaded through the aforesaid opening, the inner end of said screw abutting the rear end of said die.

5. A tool of the class described comprising a continuous yoke having parallel longitudinal sides, an opening at one end and work-engaging rollers at its other end, a die within the yoke, members secured against opposite sides of said die and lying against the opposite faces of both longitudinal sides and said one end of the yoke, removable means projecting from said faces of said longitudinal sides and said one end for movably connecting said members with said yoke, and an adjusting screw threaded through the aforesaid opening, the inner end of said screw abutting said die.

10 20 In testimony whereof I have hereunto affixed my signature.

VICTOR KALFUS.
